CHARGER MOTOR

George W. Pontius, III, South Bend, Ind., assignor to Bendix Aviation Corporation, South Bend, Ind., a corporation of Delaware

Application August 16, 1941, Serial No. 407,142

6 Claims. (Cl. 89—1)

This invention relates to gun chargers and more particularly to a fluid actuated motor for charging guns.

In the firing of guns such as machine guns and automatic cannon it is often necessary to reciprocate the breech bolt to eject a fired casing and to insert a fresh cartridge. In automatic guns the reciprocation of the bolt is performed by the firing of a cartridge, and when a dud cartridge is inserted in the gun there can be no reciprocation to eject the dud and insert a fresh cartridge. Charger motors are accordingly used to charge guns and thereby save the gunner the manual effort of the operation. This invention relates to such a charging motor, particularly for small guns requiring a small effort to reciprocate the breech bolt.

It has been found that to successfully charge automatic guns such as machine guns, the breech bolt must be allowed to return unimpeded to the firing chamber to effectively close the firing chamber. If the return spring on the bolt of a machine gun must also return the charging motor to its starting position, the breech bolt, under some conditions, will fail to close tightly, and the reloading of the gun may be incomplete. It is therefore necessary to provide a mechanism to hold the bolt in retracted position until the starting motor has withdrawn out of the path of travel of the bolt.

I have found that one desirable manner of holding the breech bolt in a retracted position until the charging motor returns to its starting position, is by means of a latch mechanism secured to the charging motor. I accordingly provide a latch to hold the bolt in retracted position and an automatic trip mechanism to release the latch when the charging motor returns to the starting position. It is sometimes possible to place the latch actuating mechanism within the charging motor as in U. S. application Serial No. 371,742, filed December 26, 1940, on behalf of Pontius and Wilson. However, the motor must be made as small as possible to save weight and in the case of small guns, for example, .30 calibre machine guns, the motor is too small to conveniently place the latch mechanism inside. The latch operating mechanism must accordingly be placed on the outside of the motor and this structure forms a part of the invention.

It is an object of the present invention to provide a simple, rugged and inexpensive charger motor for guns.

It is another object to provide a charger motor

with self-contained means to return the motor to the starting position.

It is an object to provide a charger motor having a latch mechanism to hold the breech bolt in the retracted position.

A further object is to provide a charger motor having an external trip mechanism for a breech bolt latch.

Still another object is to provide a charger motor which can be positioned on either side of a gun for the charging operation.

In the drawing forming a part of this specification:

Figure 1 is a view in elevation and partly in section showing my hydraulic motor applied to a gun indicated in dotted outline;

Figure 2 is an elevational view of a part of the motor showing the latch mechanism in position to hold the breech bolt in a retracted position; and

Figure 3 is a section along the line 3—3 of Figure 2.

In Figure 1, a machine gun 10 has a breech bolt pin 12 inserted in a breech bolt (not shown) which pin slides in a slot 14 upon reciprocation of the breech bolt. Secured to the gun 10 near either end of slot 14 is a forward bracket 16 and a rear bracket 18. Brackets 16 and 18 may be opened to place therein a cylinder 20 after which the brackets are closed and fastened, as more fully described in Pontius et al. application, Serial No. 371,742, referred to above.

The right end of cylinder 20, or the forward end with relation to the gun 10, has welded thereto an elbow fitting 22 having a stop bar 23 pinned therethrough and to which may be secured a hydraulic conduit 24. Cylinder 20 is slotted at 21 (Figure 3) on its upper side to the left of bracket 16. Within cylinder 20 is a tubular piston 26 having a head 28 and seal 30 on the right end. On the left end of piston 26 is secured an ear 32 protruding through the slot 21 and having flanges 34 on the upper and right ends. When the piston 26 is moved to the left under the influence of fluid pressure admitted through the tube 24 and elbow 22, the flanges 34 on ear 32 engage breech pin 12 and move it rearwardly or to the left, causing the bolt to be retracted, ejecting the casing or cartridge in the firing chamber. When the breech bolt is released, a new shell is inserted and the gun is again ready for firing.

Fastened in the left end of cylinder 20 is a head 36 to which is secured a guide rod (not shown) which extends axially within the cylinder to guide the left end of a compression spring

38 which returns the piston 26 to its starting position after a charging stroke. Also secured near the left end of cylinder 20 is a collar 40 which supports a roller 42. On the bottom of cylinder 20 near the left end is welded a double ended spindle 44, shown most clearly in Figure 3. Pivoted on spindle 44 is an arm 46 having spreading fingers 48 on the forward or right end and a spindle 50 on the rearward or left end on which is mounted a roller 52. Rollers 42 and 52 both lie in a vertical plane through the axis of cylinder 20. A spring 54 secured to cylinder spindle 44 and contacting arm spindle 50 tends to rotate the arm 46 clockwise so that the arm will not project into the path of bolt pin 12 as it reciprocates in slot 14 during automatic firing.

On the left end of cylinder 20 and freely slideable thereon is a collar 56 having a beveled rearward or left edge and having flattened sides. Secured to each side of collar 56 are forwardly projecting shanks 58 secured at their right or forward ends by a curved member 60 resting on the top of cylinder 20. Shanks 58 are likewise flattened as shown in Figure 3, one flat being adjacent arm 46 which allows a more compact assembly of the arm 46 on the cylinder. The lower edges of shanks 58 contact spindle 44 and collar 56 is thus kept from rotating on cylinder 20. The ear 32, shank member 60 and the right edge of collar 56 form a lost motion connection between the piston 26 and collar 56 which will now be explained.

As shown in Figure 2 the collar 56 may be moved rearwardly by ear 32 until it contacts arm roller 52. This causes arm 46 to rotate counter-clockwise until the upper finger 48 is forward or to the right of bolt pin 12, preventing it from returning to close on the breech. Roller 42 acts as a low friction bearing for collar 56 when it is pressing against roller 52. At the end of the charging stroke the fluid pressure supply may be cut off and cylinder 20 connected to exhaust by any suitable means, and the return spring 38 will force the piston 26 back to its starting position discharging fluid from the cylinder 20. As the piston approaches its starting position the ear 32 will contact the member 60 on shanks 58 and will draw collar 56 to the right away from roller 52 allowing the arm 46 to rotate clockwise and release breech bolt pin 12.

It will be noted that the charger motor is readily adapted to either side of the gun 10. For this purpose ear 32 and its flanges are constructed symmetrically to engage the pin 12 on either side. Likewise the arm 46 is provided with two spreading fingers 48 so that when the arm 46 is placed on the other end of spindle 44 and turned over so that roller 52 will still be in a vertical plane through the axis of the cylinder, there will be a locking finger engageable with the breech bolt pin to hold the breech bolt in a retracted position. The brackets 16 and 18 can be used on either side of a gun to hold cylinder 20.

In operation, the brackets 16 and 18 hold charger cylinder 20 to the gun 10. During normal firing the breech bolt will automatically reciprocate causing breech pin 12 to reciprocate in slot 14. When it is desired to charge the gun, fluid under pressure is supplied through tube 24 and elbow 22 to act against piston seal 30 causing piston 26 to move toward the rear. Ear 32 which is fastened to piston 26 and protrudes through slot 21 in cylinder 20, engages breech bolt pin 12 and forces the breech bolt rearwardly or to the

left as the piston moves under the influence of fluid pressure.

When the piston 26 reaches the end of its charging stroke, ear 32 engages collar 56 moving it rearwardly or to the left, until it contacts arm roller 52, rotating arm 46 counter-clockwise as shown in Figure 2. In this position a finger 48 of the arm 46 locks the breech bolt, through its pin 12, in a retracted position. The fluid pressure is now relieved and connected to exhaust by any suitable means. Compression spring 38 will now move the piston toward the right to its starting position, collar 56 remaining in the position shown in Figure 2.

When the piston 26 approaches its starting position the ear 32 contacts member 60 of the shank 58, pulling collar 56 toward the right. This allows arm 46 to rotate clockwise, releasing breech bolt pin 12 and allowing the breech bolt to slam shut on the firing chamber. The latch mechanism described allows the breech bolt to return to the firing position without being impeded in its travel by the charging piston 26.

Although the invention has been described with reference to a particular embodiment thereof, it is not intended to limit it to that embodiment or otherwise, except by the terms of the following claims.

What is claimed is:

1. In a mechanism for retracting the breech bolt of a gun, a cylinder, a piston in said cylinder adapted for reciprocable movement, means connected to the piston for retracting the bolt upon movement of the piston in one direction, a latching member mounted on the cylinder for holding the bolt in retracted position, and a latch controlling member mounted on and movable with respect to said cylinder and having a two-way lost motion connection with said piston for moving the latching member to a position of latching said bolt during the bolt retracting movement of the piston and for releasing the latching member to free said bolt during the return stroke of the piston.

2. For use with an automatic gun of the type having a breech bolt reciprocable during normal gun operation, a fluid motor adapted to retract said bolt upon misfire of said gun and to free said bolt for unimpeded countermovement to the firing position, comprising in combination: a cylinder, a piston movable in said cylinder, means secured to said piston for engaging said bolt to retract the same upon movement of said piston, latching means mounted on said cylinder for holding the bolt in retracted position, and means slidably mounted on said cylinder and movable by said bolt engaging means, as the piston approaches the end of its stroke during bolt retracting movement, for operating said latching means to latch the bolt in retracted position.

3. For use with an automatic gun of the type having a breech bolt reciprocable during normal gun operation, a fluid motor adapted to retract said bolt upon misfire of said gun and to free said bolt for unimpeded countermovement to the firing position, comprising in combination: a cylinder, a piston movable in said cylinder, means secured to said piston for engaging said bolt to retract the same upon movement of said piston, latching means mounted on said cylinder for holding the bolt in retracted position, and means slidably mounted on said cylinder and movable in one direction by said bolt engaging means, as the piston approaches the end of its stroke during bolt retracting movement, for operating said

latching means to latch the bolt in retracted position, said slidably means movable in the opposite direction by said bolt engaging means, as the piston approaches the end of its return stroke, for releasing the latching means to unlatch the bolt.

4. A mechanism for retracting the breech bolt of a gun comprising a cylinder having a slot therein, a piston in said cylinder arranged for reciprocation and normally urged to one end of the cylinder, a member secured to the piston and having a portion extending through the slot in the cylinder to engage the breech bolt to retract the same when the piston is moved to the other end of the cylinder, means disposed exteriorly of said cylinder and slidably mounted thereon and constructed and arranged to be moved longitudinally thereof by said member when the piston is moved to the said other end of the cylinder, and an arm constructed and arranged to be moved by the movable means into engagement with the breech bolt to latch the bolt when it is moved into the retracted position.

5. For use with an automatic gun of the type having a breech bolt reciprocable during normal gun operation, a fluid motor adapted to retract said bolt upon misfire of said gun and to free said bolt for unimpeded countermovement to the firing position, comprising in combination: a cylinder, a piston movable in said cylinder, means secured to said piston for engaging said bolt to retract the same upon movement of said piston, latching means pivotally mounted upon said cylinder to be operated for latching the bolt in retracted position and then releasing the bolt at a predetermined time, and means slidably mounted on said cylinder for operating said latching means comprising a collar encircling the cylinder, a pair of shank members connected to the collar and disposed on opposite sides of the cylinder and parallel thereto and terminating in a curved element spaced axially from the collar, said bolt

engaging means constructed and arranged to engage said collar to move said slidably mounted means in one direction to operate the latching means as the piston approaches the end of its stroke during bolt retracting movement to cause the bolt to be latched, and to engage the curved element to move the slidably mounted means in the other direction to allow the latching means to be operated as the piston returns from its bolt retracting position to cause the bolt to be released.

6. A mechanism for retracting the breech bolt of a gun comprising a cylinder having a slot extending longitudinally thereof, a piston in the cylinder arranged for reciprocation and normally positioned in one end of the cylinder, a member secured to the piston and having a portion extending through the slot in the cylinder to engage the breech bolt to retract the same when the piston is moved to the other end of the cylinder, means mounted on the cylinder for longitudinal movement and including two elements axially spaced along the cylinder to be engaged alternately by the member during reciprocation of the piston, said member normally engaging one of said elements to urge said means to the said one end of the cylinder, an arm for releasably holding the breech bolt in a retracted position and disposed in the path of movement of said other element, said member being constructed and arranged to engage the said other element to cause the arm to move to engage the breech bolt for holding the same in a retracted position when the piston is moved to the said other end of the cylinder and to engage the said one element to move said means to allow the arm to move to a position to disengage the breech bolt when the piston is returned to the said one end of the cylinder.
